UNITED STATES PATENT OFFICE.

WALTER F. TROTTER, OF CINCINNATI, OHIO.

ROTARY HAMMER.

1,366,850.

Specification of Letters Patent. Patented Jan. 25, 1921.

Application filed June 5, 1916, Serial No. 101,792. Renewed December 4, 1919. Serial No. 342,479.

To all whom it may concern:

Be it known that I, WALTER F. TROTTER a citizen of the United States, residing at Cincinnati, in the county of Hamilton and State of Ohio, have invented certain new and useful Improvements in Rotary Hammers, of which the following is a specification, reference being had therein to the accompanying drawing.

10 This invention relates to improvements in rotary hammers. The object of the invention is to provide a structure of this class which will be composed of few simple parts arranged in such way as to impart a rapidly delivered series of powerful blows with an economy of power, and which, during operation, will run steadily and smoothly, and from which will be eliminated the reactionary jars and strains that have been incident 20 to tools of this class.

Figure 1 illustrates an implement embodying my improvements, the parts being shown in vertical section on the plane of the line 2—2, Fig. 2, parts of the motor casing being in side elevation;

Fig. 2 is a front view of the implement, the lower parts being in section;

Fig. 3 is a transverse vertical section showing the hammer, proper, and its casing; 30 Figs. 4, 5, and 6 show hammers embodying my improvements but varying from each other in respect to the positions of the striking face and tool in relation to the governing centers of the mechanism, and illustrating successively hammers adapted to imp- 35 part blows increasing in force.

In the drawings there is shown a support for the operative parts, which is formed as a casing, having the upper element 1 and the lower element 6. In the chamber in the upper part 1 of the casing is placed an electric motor A. In the chamber in the lower part of the casing is mounted the hammer shaft 8. The lower part of the casing has a front 40 wall 6^a, preferably integral with its cylindrical wall; and the front end of the motor chamber is closed by a plate 1^a. The rear end of the lower chamber is closed by a removable plate 7. 11 is a concavo-convex fac- 45 ing plate which is secured to the front end of the support or casing with a joint at 11^a.

The armature shaft 8 mounted in bearing 1^b carries pinion 2 which meshes with an idle intermediate wheel 9. The latter is mounted on a shaft 10, the ends of which 50

are, respectively, seated in a socket in the front plate 1^a of the motor chamber, and in a socket in the facing plate 11. The intermediate wheel 9 meshes with a wheel 12 on shaft 8. The latter is mounted in ball bearings 6^b and 7^a, the former being supported in the front wall 6^a, and the latter in the removable rear wall 7 and covered by cap 7^b. 60

To the shaft 8 is rigidly secured the hammer carrier 13. It is formed with two arms 65 or plates 13^a and the weighted connecting part 13^b. The plates or arms 13^a are fitted snugly between the bearings 6^b and 7^a.

The hammer, proper, is indicated by 14 and comprises the outer, curved, elongated, 70 relatively wide and heavy part 14^a and the inner, web-like or thinner part 14^a. This web part is fitted loosely between the arms or plates 13^a of the carrier and is shaped to have an arm or plate 14^b extending laterally 75 or eccentrically in one direction. The hammer is connected to the carrier by means of the pivot pin 15 which passes through the plates or arms 13^a of the carrier and through the arm or plate 14^b. 16 is a slot in 80 the web part 14^a of the hammer through which passes the shaft 8. This slot permits a movement of the hammer head 14^a relatively to the carrier and the shaft, and around the axis of the pivot 15. The ham- 85 mer is, on its outer face, formed or provided with a striking head 17 with a striking face 17^b in a plane tangential to a cylinder concentric with the axis of rotation, that is the axis of shaft 8 and an edge part at 17^a. 90

The casing is formed with a tool-holding guide or bearing 18, and in this is fitted the tool 19. The latter can move outward when struck by the hammer, after which it can be again thrust inward, but to an extent lim- 95 ited by the stop 20.

Having thus specified the peculiarly shaped parts which I employ, I will call attention to the peculiar features of relative arrangement which I have designed in order 100 to obtain the most beneficial results.

For convenience of description I shall refer to the several parts of the structure in that relationship which is shown when they are considered as seen on a plane of section 105 transverse to the main axis. In such a plane the point indicating the axis of the pivot 15 is located on a radius which, (from the standpoint of the direction of rotation,) is in advance of that part of the diameter 110

which passes through the shaft axis and through the face of the striking head, and is behind or in rear of the opposite part of that diameter. I here use the term "diameter" as meaning the line which, passing through the axis of the shaft 8, extends to the inner circle of section of the casing in one direction, and also, in the other direction extends from that axis to said circle.

10 This diameter includes two equal parts to each of which I herein refer as a "radius." The line x, x' includes a "diameter" through the axis and each half of this diameter I term a "radius." The line y, y' includes a 15 diameter passing through the main axis and through the axis of pivot 15. y^3 is the point at the center of the main axis. y^2 is the end of the radius passing through the pivot 15.

The radius y^2, y^3 is in advance of that 20 part of the diameter included in line x, x' (or that radius) which passes through the striking face 17^b, and is behind the other part of the same diameter (that is to say, the other radius) which extends in the opposite 25 direction toward x' .

The shaft and carrier rotate at a speed of from one thousand (1000) to fifteen hundred (1500) revolutions per minute. During such rotation the hammer tends to 30 swing out, centrifugally, about the pivot 15. The outward movement is positively limited by the shaft 8, against which the hammer is normally held by the centrifugal force.

35 The striking head 17 I locate peculiarly in relation to the center of gravity, the center of gyration, and the center of percussion of the hammer. For the purpose of illustration, I have indicated, diagrammatically, in 40 the drawings, these three centers, respectively, at a, b and c . On the outer face of the hammer I arrange the striking head so that the point of contact with the tool at the time of imparting the blow will be at the 45 center of percussion or will be on a line tangent at that center to an arc struck from the axis of the shaft.

In Figs. 2 and 3 the parts are so constructed and arranged that the axial plane, 50 which includes the center of gravity a , is considerably in advance of the axial plane which intersects the striking head, and the center of percussion is outside the periphery of the curved part of the hammer head.

55 In Figs. 4, 5 and 6 the radial plane of the gravity center intersects the striking face, the center of percussion being in that face and in that plane. The inner end or anvil end of the tool 19 projects into the path of 60 the striking head 17 a predetermined distance, which distance is related to the relative movements of the hammer which result from its rotation, from its rebounding, and from its stopping at the axis.

65 I herein, at one point or another, use the

terms "axial plane" and "radial plane," and in each instance mean a plane containing the axis of the shaft 8.

As concerns the matter of rebounding, an important feature of my construction is that 70 I hinge or locate the axis of the pivot 15 in such way as to have the axial plane of this axis forward of the axial plane passing through the hitting face, and with such an angular distance between these planes (other factors being considered) that the pivot, connected to the hammer, will not seriously interfere with the hammer following the natural lines of rebound after the instant of 75 blow impact.

The tangent from the center of percussion c passes through the blow point or percussion point on the striking face 17^b, and this tangent is the line of the blow to be regarded. But the entire matter can be considered in terms of the center of gravity a . The line at I , passing through the center of gravity, can, therefore, for all intents and purposes of explanation, be taken as being the same as the tangent referred to. And 80 the line $T-U$, parallel to the striking face, can be regarded as the line containing the point at which the blow is struck. If the gravity center point a is regarded as moving along the line I , and striking the line $T-U$, it will, if free to move, rebound along the line J , and the angle of the incidence of the blow is equal to the angle of rebound; that is to say, the angle $I-a-T$ is equal to 85 the angle $J-a-U$.

As shown in the drawings, the striking point is in that quarter of the cycle which is between the right hand horizontal radius and the lower part of the vertical diameter. And the pivot 15, which holds the hammer to the carrier, is in the fourth of the cycle in advance of the one referred to. When this pivot 15 is moving through the first part of this fourth of a cycle, the hammer is held at its outermost limit by centrifugal force. But just before the pivot 15 reaches the horizontal diameter (as in Fig. 5), the blow is struck and the gravity center a is caused to travel toward the left. The desideratum is to have it travel on a line 105 which is forward of the line J extending from the center of gravity to the main center of rotation and approximately radial to the axis of its pivot. In Fig. 5 this line J through the point a , where the center of 110 gravity begins its rebounding movement, and through the point a' , where it terminates this movement, is on a radius through the main axis. But I have found it preferable to have this line J at some inclination to the radius through the main axis, as shown in Fig. 4 and Fig. 3; that is to say, I prefer to so position the parts that the line along 115 which the center of gravity rebounds will extend from said center to the left of the 120

axis of shaft 8 when looking as in Figs. 2 to 6, and will approximate a radial position relative to the axis of its pivot 15 shown in dotted lines, Fig. 4. This relieves the 5 machine from the stresses incidental to starting the hammer on its forward movement while it is moving in a direction opposite to the direction of rotation. In connection with this rebounding of the hammer, it is to be noticed that, during this 10 movement, the striking head 17 smoothly and easily escapes from the anvil end of the tool. The rounded corner and the edge 17^a of the striking head are so designed as to 15 provide for this easy escape of the striker, although a severe blow has been struck the previous instant.

The rebounding continues until the lower end of the slot 16 comes to the center stop 20 (in this case, the shaft 8), this occurring at the time the striking head 17 is at its innermost position, as aforesaid, far enough to permit it to pass the tool.

The dotted lines indicate the position 25 which the hammer takes at the termination of its rebounding, the pivot 15, at that instant, having been moved from the full line positions to those in dotted lines.

I do not mean to be understood as saying 30 that all the advantageous features are dependent upon having the lines of rebound of the hammer such that the center of gravity will rebound on a line extending from said center to the left of the axis of 35 shaft 8 when looking as in Figs. 2 to 6. Under some circumstances, I may sacrifice some of the matters above described and arrange the parts as shown in Fig. 6. Here the parts are so constructed and related that 40 the horizontal line through the center of gravity *a*, parallel to the striking face, is relatively so elevated as to include or approximate the axis of the pivot 15, the latter being set relatively lower than that in the 45 constructions in Figs. 4 and 5, and the axial plane through the pivot 15 being at a greater angle to the plane through the center of gravity. The blow, struck when the center of gravity is traveling on the 50 line *I*, causes the center of gravity to rebound along the line *J* (Fig. 6), which extends from the center of gravity along the line at the right of the main axis when looking as in Fig. 6. It will be seen that 55 a distinct effort must be exerted at the pivot and energy must be consumed to overcome the inertia of the hammer, when comparison is made with the actions of the devices in Figs. 4 and 5; the energy of rebound with the parts in Fig. 6, having a negative effect on the forward motion of the mechanism. These matters are fully 60 illustrated in the comparative views, Figs. 4, 5 and 6. Inferior results are attained 65 when the parts are constructed and arranged

as in Figs. 5 and 6 in comparison with the construction and arrangement in Fig. 4. However, there are other features of advantage incident to such constructions as that in Fig. 6, such as the disposition of the hammer metal in relation to the striking face, the mode of pivoting, and the stopping at the axis. 70

The striking face can be located in the radial plane of the center of gravity or in 75 the rear of that plane, provided the face is intersected by a tangent through the center of percussion. The center of gravity is positioned in an axial plane bisecting the hammer head. That is to say, the amount of 80 hammer head metal in advance of the axial plane of the center of gravity is approximately equal to the amount in the rear of that plane. If the striking face is in the radial plane of the center of gravity, as in 85 Fig. 5 and others, there is substantially as much hammer head metal in front of the impact point as there is behind it. It has been customary in making rotary hammer mechanisms to so arrange the hammers as to have 90 their hitting faces forward of the gravity centers. But I have found, upon careful investigation, that it is impossible, with parts so made and arranged, to get the results that 95 I attain, and particularly with small compact tools, where I position a large part of the metal of the hammer head forward and a large part in the rear of the striking face.

With respect to the use of the central shaft as a device for limiting the swinging 100 movements of the hammer, it is to be noted that a stop for this purpose either must be stationary or must be one that will rotate in the same direction with the hammer but at a much slower speed. The stop which 105 I employ is stationary and located at the central axis of the machine. It need not be a body extending continuously across the center, as shown. It may be composed of one or more stops on the frame, provided 110 they are arranged at the axis.

Considering the mechanism shown as a specific form of embodiment of the invention, there are numerous important features of advantage incident to it. The hammer 115 casing is completely inclosed. The interior chamber is cylindrical and unobstructed, and the hammer structure has only the two elements, which are closely centered and compactly arranged. One is the carrier element having the peripherally expanded momentum weight, and the other is the hammer element which counterbalances the weight element 13^b, the hammer having the elongated curvilinear head which is placed 120 diametrically opposite to the weight part, the two being arranged to provide an approximately cylindrical mass which maintains a uniformity of rotation, even at high speed, and without jolting or jarring any 130

of the shafts or bearings. In addition to the advantages above described, as incident to the relative arrangement of the pivot 15, is the fact that, being close to the weight metal, it leaves a large part of the cylindrical space available for a hammer structure of a short radius and which, though in a small chamber, is relatively large and heavy.

10. What I claim is:

1. A rotary swing hammer having a hammer head pivoted on an axis parallel to the axis of rotation and formed with a striking face in a plane tangential to a cylinder around the axis of rotation and arranged to be intersected by the plane including the axis of rotation and the center of gravity.

2. A rotary hammer having a hammer head pivoted on an axis of rotation and formed with a striking face in a plane which includes the center of percussion and is tangential to a cylinder around the axis of rotation, the head having its center of gravity and the said center of percussion in a common plane which also includes the axis of rotation.

3. The combination of the rotary carrier, its shaft, the hammer pivoted to the carrier and having an elongated curvilinear head, the pivot plate, and the slot with stops at the ends thereof adapted to engage with the shaft.

4. The combination of the casing having an inclosed cylindrical chamber and the rotary hammering structure therein comprising a rotary carrier formed with a momentum weight on one side of the axis of rotation, and the centrifugally moving hammer having an elongated curvilinear head approximately concentric with the axis of rotation and arranged diametrically opposite to said momentum weight and having also a pivoted arm and a slot in said arm to provide stops, a stationary stop at the axis of rotation to engage the stops provided by the slot.

5. The combination of the casing having a tool support, the rotary carrier in the

casing having a momentum weight on one side of the axis of rotation and a swinging hammer pivoted to the carrier and formed with an elongated curved head diametrically opposite to the momentum weight, and a pivot arm for the hammer hinged to the carrier at points near the momentum weight and having a projection extending outward from and between the ends of the curved head, which projection is provided with a striking face in a plane tangential to a cylinder around the axis of rotation.

6. A rotary hammer having a hammer head rotating around a fixed axis and pivoted on a rotating axis parallel to the axis of rotation, and formed with a striking face, through which passes the plane that includes the center of gyration and the center of gravity of the head.

7. A rotary hammer having a hammer head rotating around a fixed axis and vibratable around an axis which rotates around said fixed axis, said head having a striking face intersected by the plane which includes the center of percussion, the center of gyration and the center of gravity.

8. A rotary hammer having a hammer head rotating around a fixed axis and vibrating on an axis which rotates around said fixed axis, said hammer head having a striking face intersected by the plane which includes the center of gravity, the center of percussion and also, at the instant of the stroke, includes said fixed axis.

9. A rotary hammer having a hammer head rotating bodily around a fixed axis of rotation and movable relatively to said axis and formed with a striking face in a plane having one or more of its lines included in the plane, which also includes the center of percussion and the center of gravity of the mass of the hammer head.

In testimony whereof I affix my signature in presence of two witnesses.
